UNITED STATES PATENT OFFICE.

JOHN A. HOLZAPFEL, OF JACKSON, MICHIGAN.

WRINGER FOR ANCHOR ROPES.

Application filed February 12, 1923. Serial No. 618,537.

To all whom it may concern:

Be it known that I, JOHN A. HOLZAPFEL, a citizen of the United States, residing at the city and county of Jackson, State of Michigan, have invented certain new and useful Improvements in Wringers for Anchor Ropes, of which the following is a specification.

This invention relates to improvements in wringers for anchor ropes.

The main object of the invention is to provide an improved wringer for anchor ropes which effectively removes the surplus water therefrom as the rope is hauled into the boat and at the same time is comparatively easy to operate and permits the rope to run freely when paid out to lower the anchor.

A further object is to provide an improved wringer for anchor ropes which is simple and economical in structure and durable and strong.

Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing forming a part of this application, in which:

Fig. I is a vertical longitudinal section on a line corresponding to line 1—1 of Fig. II.

Fig. II is a rear elevation.

Fig. III is a side elevation of a modified structure, the modification being in the form of a mounting for the pulley block.

Fig. IV is a vertical longitudinal section on a line corresponding to line 4—4 of Fig. V of another modified form of my invention.

Fig. V is a vertical section on a line corresponding to line 5—5 of Fig. IV.

Fig. VI is a side elevation of another form or embodiment of my invention, one of the side plates of the pulley block being opened to better illustrate the parts, certain parts being for convenience shown in section and other parts broken away.

Fig. VII is a detail view on a line corresponding to line 7—7 of Fig. VI.

In the drawing the sectional views are

taken looking in the direction of the little arrows at the ends of the section lines and similar reference characters refer to similar parts throughout the several views.

Referring to the drawing, in the embodiment shown in Figs. I and II, I provide a pulley block comprising a base plate 1 adapted for attachment to a boat indicated at 2, and spaced side plates 3, 3. These are preferably in the form of an integral casting and the pulley block preferably has an eye 4 for the attachment of a painter. The anchor rope is indicated at 5.

In the preferred illustration in Figs. I and II I provide a relatively fixed wringer 6 which is mounted on the journal pin 7 extending between the side plates. A coacting movable wringer pulley 8 is carried by the actuating lever 9 mounted on the pivot 10 extending between the side plates.

On the rear end of this actuating lever 9 is an actuating pulley 11, the rope 5 being passed over the pulley 6 and under the pulley 11, so that a pull on the rope 5, as in hauling in, the anchor forces the pulley 8 downwardly upon the rope and the water is wrung or squeezed therefrom as the rope is hauled in.

In the modification shown in Fig. III, a pivoted attaching plate 12 is provided for the pulley block, this plate being pivoted at 13 to the depending ears 14 on the pulley block and being adapted to receive a screw as indicated by dotted lines at 15.

It will be understood that boats used for fishing boats, particularly on inland lakes, are of various shapes, many being "home made" and the stern or prow is sometimes merely a board or plank. These are sometimes set vertically and sometimes at an angle. By means of the pivoted attaching plate 12 the pulley block may be effectively mounted on different types of boats.

In the modification shown in Figs. IV and V, the relatively fixed wringer pulley 16 and the movable wringer pulley 17 are disposed with their journals in a horizontal plane. The actuating lever 18 on which the movable wringer pulley is mounted is provided with a shoe 19 over which the rope is passed in lieu of the actuating pulley 11.

In the modification shown in Figs. VI and VII, the base plate 20 is adapted to be mounted upon a boat and the base plate 21

of the pulley block is detachably engageable with this base plate 20. However, the details of such engagement form no part of this invention and are, therefore, not described herein.

The pulley block base plate 21 has a fixed side plate 22 and a pivoted side plate 23. The pivoted side plate 23 is pivoted to the top of the fixed side plate 22, a staple 24 being carried by the fixed side plate and adapted to pass through a hole 25 on the pivoted side plate so that a lock may be engaged in the staple for securing the pivoted side plate.

15 The wringer pulley 26 is mounted on a fixed stud 27 carried by the fixed side plate. A coacting wringer pulley 28 is provided with a floating spindle 29 which engages the slots 30 and 31 in the side plates. These 20 slots are inclined so that, as the spindle 29 is moved in the slots, the pulley 28 is carried to and from the coacting pulley 27 to open and close the wringer upon the rope 5.

An actuating pulley 32 is supported by 25 the journal or spindle 33 in the slots 34 and 35 of the side plates. The slots 34 and 35 are at an angle to the slots 30 and 31. The spindles 29 and 33 are connected by links 36 so that, as the actuating pulley 32 is moved rearwardly by a hauling pull on the rope, the movable wringer pulley is moved towards its coacting wringer pulley.

My improved rope wringer is simple in structure and at the same time is very efficient.

I have illustrated and described my improvements in several embodiments or adaptations which will I believe enable those skilled in the art to which my invention relates to embody or adapt the same as may be desired.

Having thus described my invention what I claim as new and desire to secure by Letters Patent is:

45 1. In a device of the class described, the combination of a pulley block comprising side plates, a relatively fixed wringer pulley journaled between said side plates, an actuating lever pivotally mounted between said side plates, a movable wringer pulley mounted on the forward end of said actuating lever above said fixed wringer pulley to coact therewith, and an actuating pulley mounted on the rear end of said actuating lever so that a pull on the rope passed over said fixed wringer pulley and under said actuating pulley will force said movable wringer pulley downwardly toward said fixed wringer pulley.

55 2. In a device of the class described, the combination of a pulley block comprising side plates, a relatively fixed wringer pulley journaled between said side plates, an actuating lever pivoted between said side plates, a movable wringer pulley mounted

on said actuating lever to coact with said fixed wringer pulley, and an actuating pulley on the rear of said lever disposed to be engaged by the rope so that a pull thereon will force the movable wringer pulley 70 toward the fixed wringer pulley.

3. In a device of the class described, the combination of a pulley block comprising side plates, a relatively fixed wringer pulley journaled between said side plates, an actuating lever pivotally mounted between said side plates and provided with a rope 75 engaging pulley at its rear end, and a movable wringer pulley mounted on the forward end of said actuating lever above said fixed wringer pulley to coact therewith.

4. In a device of the class described, the combination of a pulley block comprising side plates, a relatively fixed wringer pulley journaled between said side plates, an actuating lever pivotally mounted between said side plates and provided with a rope 80 engaging member, and a movable wringer pulley mounted on said actuating lever to coact with said fixed wringer pulley.

5. In a device of the class described, the combination of a pulley block, coacting wringer pulleys, one of which is movably supported, a movably supported actuating pulley with which the rope is engaged, and connections for said actuating pulley to said movably supported wringer pulley so that when the rope is hauled in the wringer pulleys are closed and when it is run out the 95 said wringer pulleys are opened.

6. In a device of the class described, the combination of coacting wringer pulleys associated to be opened and closed upon a rope, a movably mounted actuating pulley disposed at the rear of the wringer pulleys with which the rope is engaged, and operating connections from said actuating pulley to said wringer pulleys whereby a hauling pull upon the rope will close the wringer pulley and the paying out of the rope will 105 open the wringer.

7. In a device of the class described, the combination of a wringer adapted to be closed or opened to free the rope, an actuating pulley disposed at the rear of the wringer, and operating connections from said actuating pulley to said wringer whereby a hauling pull upon the rope will close the wringer upon the rope and the paying out of the rope will open the wringer.

8. In a device of the class described, the combination of coacting wringer pulleys, one of which is movably mounted, a movably mounted actuating member with which the rope is engaged, and operating connections from said actuating member to said movably mounted wringer pulley, said actuating member being disposed so that a hauling pull upon the rope will close the wringer pulleys.

9. In a device of the class described, the combination of coacting wringer pulleys, an actuating member disposed at the rear of said wringer pulleys, and operating connections for said actuating member to said wringer pulleys whereby on the hauling in of the rope the wringer pulleys are closed and on the running out of the rope they are separated.
10. In a device of the class described, the combination of coacting wringer pulleys, one of which is movably mounted relative to the other, a movably mounted actuating member over which the rope is passed, and operating connections for said actuating
- 5 member to said movably mounted wringer pulley.
11. In a device of the class described, the combination of a pulley block provided with a base plate adapted to receive attaching screws whereby the pulley block may be attached to a surface of a boat, and a supplemental attaching plate pivotally connected to said base plate whereby it may be disposed upon and secured to an adjacent surface.
- 10
- 15
- 20
- 25

In witness whereof, I have hereunto set my hand and seal.

JOHN A. HOLZAPFEL. [L.S.]
